UNITED STATES PATENT OFFICE

MORRIS SALINGER, OF NEW YORK, N. Y., ASSIGNOR OF ONE-HALF TO EMANUEL D. STEIN, OF NEW YORK, N. Y.

DESIGN FOR A CLOCK CASE

Application filed May 14, 1930. Serial No. 35,641. Term of patent 7 years.

To all whom it may concern:

Be it known that I, MORRIS SALINGER, a citizen of the United States, residing at New York city, New York, county of New York, and State of New York, have invented a new, original, and ornamental Design for a Clock Case, of which the following is a specification, reference being had to the accompanying drawings, forming a part thereof.

In the drawings:

Figure 1 is a front elevational view of a clock case showing my new design, and

Figure 2, is a side elevational view of the same.

I claim:

The ornamental design for a clock case substantially as shown.

MORRIS SALINGER.
